4 Claims. (Cl. 241—255)

This invention relates to a defibrator particularly for refining paper stock and the object of the invention is to provide a defibrator which is more effective and gives a better product than defibrators heretofore used.

The principal characteristics of the defibrator according to the invention are set forth in the accompanying claim 1.

In the Finnish Patent No. 33,051 is a refiner disclosed particularly for the refining paper stock, in which the diameters of the various zones increase in the feeding direction, but in which the surfaces of the zones are parallel to the axis of the rotor, in which case it is not possible to achieve a continuously accelerating movement of stock during its movement in each zone and therefore not an improved defibration simultaneously with substantial decrease of the passage time of stock, the result improving irrespectively.

In the German Patent No. 1,177,466 a disc refiner is disclosed wherein the refining discs are divided into zones which in the direction of the disc axis are displaced with respect to each other and in which the gap in each zone decreases towards the periphery, and at the transit from one zone to another there is an axial transit zone consisting of plates, the gap in said transit zone being, however, equal to the gap in the previous zone, so that no pressure drop results in the stock stream.

The invention is described more fully in the following, with reference to the accompanying drawing which as an example shows a defibrator according to the invention in longitudinal section.

In the drawing the reference numeral 1 indicates a rotor of the defibrator and 2 a stator drum, which both are divided into three conical zones 3, 4, 5 and 6, 7, 8 respectively. At the feed end of the rotor 1 there is provided a screw feeder 9 rotating together with the rotor and located in a feeding channel 11 situated at the center of a housing 10. The stator 2 is bolted by the bolt 12 to the housing 10. The housing 10 in turn is through an intermediate ring attached to a frame 14 by means of bolts 15, thus forming adjacent the intermediate ring a stock discharge space 16 of the defibrator, from which space the stock is discharged in a known manner.

The base angle of the cones of the conical zones of the rotor and stator 3, 4, 5 and 6, 7, 8, respectively is greatest in zones 3 and 6 and decreases being smallest in zones 5 and 8. At the transit from one conical zone of the rotor 1 to another the base portion of zones 3 and

2

4 have cylindrical zones 17 and 18 which each terminate at walls 19 and 20 perpendicular with respect to zones 17 and 18 and defining the zones 4 and 5 respectively, opposite which walls 19 and 20 and at a distance 5 from them corresponding to the width of the zones 17 and 18 the stator 2 has corresponding parallel walls 21 and 22 and cylindrical zones 23 and 24 parallel to zones 17 and 18. Thus there are formed two annular extensions or pockets 25 and 26, greater than the normal gap between the rotor 1 and the stator 2 at the travel path of the stock.

As the stock stream moves between the stator and the rotor at increasing speed in each zone and reaches the extension there occurs a sudden pressure drop in the stock and further a relatively great change of flow direction, which facts have a favourable influence on the breaking up of eventual fibre bundles.

The invention is not restricted to the embodiment described and shown only as an example but can be modified in many ways within the scope of the accompanying claims. Thus e.g. zones 18 and 17 need not necessarily be parallel to the rotor axis but can have a conicity similar to that of the zones 3 and 4 or even differing from the same.

25 What I claim is:

1. Defibrator particularly for refining paper stock, comprising rotatable rotor provided with bars and a stationary stator drum mounted around the same and preferably provided with bars, the rotor and stator both being divided into at least two zones having an increasing diameter in the feeding direction of the stock, characterized in that the zones are conically widening in the feeding direction and that the base angle of the cone decreases from zone to zone in the feeding direction of the stock.

30 2. The defibrator according to claim 1, characterized in that at the transit point between zones there is an extension greater than the gap between the rotor and the stator elsewhere.

3. The defibrator according to claim 2, characterized in that the cross section of the extension at the transit point between zones is rectangular.

45 4. The defibrator according to claim 3, characterized in that the surface of the rotor adjacent to the extension is parallel to the axis of the rotor and that the extension extends to the feeding gap of the following zone.
